UNITED STATES PATENT OFFICE.

HERMAN J. WILLHAGEN, OF DETROIT, MICHIGAN.

VARIABLE-ARC FIN CONDENSER.

Application filed June 2, 1925. Serial No. 34,347.

The object of my invention is to produce a radio condenser that can be manufactured from cast metal parts, and assembled by inserting one casting within another, and in such a way that the capacity may be varied as desired by a rotation of one of the castings.

Another object is to produce a variable condenser for a radio receiving set, that the two separated sections may be each cast in a single solid piece, thus greatly reducing the manufacturing cost of the instrument.

A further object is to produce a circular arc fin condenser which will practically prevent any dust particles from settling therein, as it is well known that the presence of dust greatly decreases and destroys the capacity of the instrument.

A still further object is to produce a variable condenser having all of its projecting fin plates formed of a single solid piece casting, to eliminate poor contact and avoid any readjustment of the plates after assembling which frequently cause a short in the instrument, and to provide a condenser that is simple in construction, but effective in its operation and can be manufactured at a very low cost.

These several objects are attained in their preferred form by the construction and arrangement of parts more fully hereinafter set forth.

Similar parts on all drawings are marked by similar numerals.

Fig. 1, is a plan view of a double quadrant condenser, each section comprising a quarter of a circle, having the alternate quadrants vacant.

Fig. 2, is a sectional view —AA— of Fig. 1, showing the general construction of the condenser, and the alternate interweaving of projecting arc fins of the rotor and the stator castings.

Fig. 3, is a sectional view of the stator casting.

Fig. 4, is a sectional view of the rotor casting showing the construction of the fin members.

Fig. 5, is a front view —BB— of Fig. 3, showing the concentric circular arc fin members, and their relative position on the segment castings.

Fig. 6, shows an alternate design of the instrument where the rotor and stator sections are made in a full half circle instead of two separated quadrant sections.

Fig. 7, is a side view of Fig. 6, showing the stator section in a partially opened position.

Fig. 8, is a sectional view of the stator section taken on the line —CC— of Fig. 6, showing the circular fin plates and the insulating means separating same from the rotor section.

Fig. 9, is also a sectional view corresponding to Fig. —8—, but of the rotor section of the device.

Fig. 10, is a front view of the stator section as seen from the section line —DD— on Fig. 8.

I will now describe more fully the detailed construction of my device, referring to the drawings and the marks thereon.

It is known that there are variable plate condensers for radio use on the market at the present time, but which are formed of a series of separated flat plates mounted with interposed separators between them, and positioned to pass between a corresponding set of like plates.

The general construction of my variable condenser comprises two circular, segment, fin castings, both mounted on a common shaft passing through the center of the castings, and is provided with insulating bearings thereon for completely insulating each segment casting from the other. Each casting is provided with circular fin plates projecting therefrom, and so positioned on each casting as to alternately overlap and interleave with the circular fin plates of the other casting, and without forming any contact therewith.

While my condensers may be made in either a double quadrant section, as shown in Fig. 1, or in a semi-circular section, as shown in Fig. 6, I prefer to use and describe more particularly the double quadrant type, and to which the specifications will more specifically refer.

The sector casting —1— is preferably made of aluminum casting, or turned from a solid aluminum piece, and comprises two circular quadrant sections —a— and —b— joined together at the center by a hub —2—, the quadrant sections being positioned diametrically opposite to each other on the hub —2—. The hub —2— is cylindrical in form, and projects both inside and outside of the cast stator plate —1—, and is arranged at right angles thereto. Cast to, and projecting from one side of the stator plate —1— are a series of concentric, circular arc fin plates

- 4— extending the full width of the sector segments of the frame —1—, and positioned concentric with the axis of the center bearing shaft —3—, which passes through the center of the hub —2—. The circular segment fin plates are formed to a true circular arc, preferably slightly tapered toward the outer edges thereof, and all project from the stator plate —1— at right angles thereto.
- 10 While the stator casting —1—, illustrated in the drawings, shows the use of only four plate fins, any number of circular arc fin plates may be added thereto, depending upon the capacity of condenser desired. The center hub —2— is provided with a counter bore —5— therein, provided with a cylindrical shoulder —6— for receiving and retaining a fixed bearing —7— of insulating material, such as fiber or rubber, and which bearing is
- 15 sufficiently fastened with cement, or by a pressed fit, to withstand the turning of the inclosed shaft —3— passing therethrough. The hub —2— projecting from the outside of the frame —1— is provided with threads —8—, concentric with the hub —2—, and through which the shaft —3— and insulator bearing —7— also pass. The hub —8— being mainly for the purpose of passing through and connecting the stator —1— to a
- 20 supporting panel —10—, and fixedly attaching same thereto by means of the threaded nut —9— engaging the threaded portion of the threaded hub —8—, which can be screwed firmly against the inclosed panel support.
- 25 The bearing shaft —3— is fitted snugly within the insulated bearing —7— for the purpose of preventing free movement of the shaft —3— and attached rotor section, except when turned by the operating dial —11— which is fixedly attached to the outer end of the shaft. To the inside end of the shaft —3— and fixedly attached thereto, is the rotor casting —12—, also made of a metallic casting of material similar to the stator
- 30 section —1—, comprising two circular quadrant sections —c— and —d—, also positioned on opposite sides of a central hub —13— mounted on the bearing shaft —3— and projecting therefrom and at right angles thereto. The hub —13— projecting slightly inside of the rotor frame —12—, engages the end of the insulator bearing —7—, for holding the rotor and stator sections apart, and completely insulating one from the other.
- 35 Like the stator section, series of concentric, circular arc fin plates —14— are cast thereto and projecting therefrom, all of said circular fin plates being formed in a true circular arc and positioned concentric with the central bearing shaft —3—, and to alternately overlap and interleave with the circular fin plates —4— of the stator section —1—, yet without touching or forming any contact therewith. The two sections are thoroughly insulated from each other. The rotor casting
- 40 —12— is fixedly attached to the shaft —3— by the set screw —15— passing through the hub —13— and engaging the side of the shaft. At the end of the shaft —3— is attached a flexible circuit wire —16— for connecting the rotor section —12— into a circuit. Also attached to the outer wall of the stator casting —1— is a small wire connector —17— for connecting the stator in the same circuit in which the condenser is used. The purpose of the device being for regulating and varying the amount of capacity required in the circuit, and its capacity is varied by the amount of surface of overlapping of the arc fin plates of the rotor section with the stator section, as the rotor fins are turned into the spaces between the stator fin plates, until the full sections of both castings coincide. The capacity of the condenser may be increased by increasing the size or the number of the arc fin plates on the stator and rotor castings. The principle and operation is always the same.
- 45 An alternate design, but having exactly the same principle and application, is shown in Figs. 6 to 10 incl. The general construction and operation being exactly the same as in the design heretofore described, except both the rotor section —18— and the stator section —19— are formed in a half circle, instead of two separated quarter segments as illustrated in Fig. 1. The circular arc fin plates —20— and —21— as project from the rotor and stator sections, are likewise formed and positioned as heretofore set forth, alternately overlapping and interleaving with the circular arc fin plates of the opposite section, each section being thoroughly insulated from each other by the insulator bearing —22— firmly pressed into the stator hub —23—. The sections are provided with the same shaft —3— and circuit connectors —16— and —17—, as is shown in the preferred type heretofore described, and the device operates in exactly the same manner. The capacity of the condenser being the same as of the former design, but requires the turning of the bearing shaft and attached rotor section —18—, a distance twice as far as would be required for the double quadrant sector shown in Fig. 1.
- 50 Having fully described my variable condenser, what I claim as my invention and desire to secure by Letters Patent is:
- 55 1. A circular arc fin condenser adapted for varying and changing the capacity in a radio circuit, comprising circular sectioned metal stator and rotor sections, each section being formed with a center hub and having a series of concentric, circular arc fin plates projecting from one side thereof and from a single piece of metal, both mounted on a common shaft, each of said circular arc fin plates being so arranged about the center hub as to alternately overlap and interleave with the

circular arc fin plates of the opposite section, but without touching or forming any contact therewith, means for insulating the rotor section from the stator section, means for turning the rotor fins through between the fins of the stator sections about the common center shaft, means for fixedly attaching the stator section to a fixed supporting panel, and means for connecting the two sections into a radio circuit.

2. A circular arc fin condenser adapted for changing the capacity within a radio circuit, comprising two metal segment castings, each of said castings provided with a series of concentric circular arc segment fin plates all cast thereon as a single piece of metal, all positioned about a center bearing through the casting, said circular arc segment fin plates being positioned at right angles to the casting, and are a part of said casting, arranged to overlap and interleave between the circular arc fin projections of the opposite section, a common bearing shaft for mounting both of the castings thereon through the center bearing therein, means for thoroughly insulating the said castings from each other, means for fixedly attaching one of the castings to a supporting panel, means for fastening the other casting fixedly to the common shaft passing through both sections of castings, means for rotating said shaft and attached casting so that its circular arc fin projections will pass

through the spaces between the circular arc fin projections of the opposite fixed casting, and without forming any contact therewith, and means for connecting the two insulated sections into a single inductive circuit.

3. A variable condenser adapted for regulating the capacity of a radio circuit, comprising a cylindrical metal bearing shaft, two circular segmental metal castings mounted on said bearing shaft, positioned at right angles thereto, means for insulating the two metal castings from each other, a hub for fixedly attaching one casting to a supporting panel, means for fixedly attaching the other casting to the bearing shaft which passes through both of said castings, each of said castings being formed with a series of concentric, circular arc fin projections cast thereon all as one single piece of metal and projecting from the sides thereof and so positioned as to all lie in concentric circles about the axis of the common bearing shaft and to overlap and interleave with the circular arc fin projections of the opposite casting section without touching or forming any contact therewith in any way, a circuit wire connected to the center shaft, and a circuit wire connected to the outer wall of the fixed casting for placing the instrument within a common circuit.

In witness whereof I sign these specifications.

HERMAN J. WILLHAGEN.
